UNITED STATES PATENT OFFICE.

HENRY M. STEVENSON, OF PERRY, IOWA, ASSIGNOR OF ONE-HALF TO
CLARENCE E. BEAVER, OF PERRY, IOWA.

VETERINARY INSTRUMENT.

SPECIFICATION forming part of Letters Patent No. 787,594, dated April 18, 1905.

Application filed June 14, 1904. Serial No. 212,538.

To all whom it may concern:

Be it known that I, HENRY M. STEVENSON, a citizen of the United States, residing at Perry, in the county of Dallas and State of Iowa, have 5 invented certain new and useful Improvements in Veterinary Instruments, of which the following is a specification.

This invention relates to improvements in that class of instruments commonly used in the practice of embryotomy; and the essential feature of the invention is comprised in the peculiar construction and mounting of the embryotome which is used in connection with the instrument, whereby same may be readily manipulated in the removal of the fetus being operated upon.

The majority of instruments of the class to which my invention relates in dismembering a fetus preparatory to its displacement from the body of the mother must be entirely removed from operative position in order to adjust the embryotome, and this is the cause of no small amount of inconvenience and loss of time, as will be readily apparent. It is therefore a desideratum that the embryotomy knife or hook, as the case may be, should be susceptible of various adjustments as the same is being used and while within the body of the animal from which the fetus is being removed, and this is readily attained in the practical embodiment of my invention.

For a full description of the invention and the merits thereof and also to acquire a knowledge of the details of construction of the means 35 for effecting the result reference is to be had to the following description and accompanying drawings.

While the essential and characteristic features of the invention are susceptible of modification, still the preferred embodiment of the invention is illustrated in the accompanying drawings, in which—

Figure 1 is a perspective view showing the pivoted knife mounted in operative position 45 upon the instrument. Fig. 2 is a sectional view, the shank being broken away, showing the hook in position thereon. Fig. 3 is a detail perspective view of the head.

Corresponding and like parts are referred

to in the following description and indicated 50 in all the views of the drawings by the same reference characters.

The instrument herein described is especially adapted for use in operating upon live stock and consists of the shank 1, provided at 55 one end with the handle 2 and at the other end with a tubular portion 3. The tubular portion 3 is internally threaded, as at 4, and a head 5 is adapted to be screwed into the part 3, being also threaded at 6 for this purpose. The head 5 is provided with a longitudinal slot 7, which is open, as shown at 8, to admit of insertion of the shank of the hook 10 or knife 11 therein. The shank 9 of the hook 10 is rigid, being integrally formed 60 therewith, whereas the shank 9^a of the knife 11 pivotally supports the said knife. A pivot-pin 12 attaches the knife 11 to its shank 9^a, and the shanks of all the embryotomes are provided with a head 13 and an adjacent annular groove 14. The portion of the shank having the groove 14 is received in the slot 7 of the head 5 when the embryotome is in operative position thereon, making a swiveling 70 or revoluble connection.

The hook 10 or knife 11 is held in position upon the shank 1 of the instrument by the clamping action of the tubular portion 4 against the shank 9 or 9^a, and the portion 4 is adapted to be forced into engagement with 75 the shank 9 or 9^a by a screwing movement of the same upon the head 5. In screwing the shank 1 upon the head 5 the tubular portion 4 when engaging the embryotome will cover the open portion 8 of the slot 7, and thus 80 all likelihood of displacement of the hook or knife is obviated.

The hook 10 when attached to the head 5 is adapted to swivel thereon and may be readily turned in the desired direction by a slight 85 unscrewing movement of the shank 1 to disengage same from the shank 9. The hook further projects at an angle from the shank, and this is advantageous in facilitating the removal of the fetus. The knife 11, because of 90 its pivotal mounting, is susceptible of many variations in adjustment, some of which are indicated in dotted lines.

- In actual operation to adjust the embryotome when within the body of the animal from which the fetus is being removed same is grasped in one hand and the shank 1 is unscrewed by the other hand until the portion 4 is disengaged from the shank 9 or 9^a. This done, the embryotome may be properly adjusted, after which the shank 1 is again screwed upon the head 5 to rigidly hold the instrument parts in place. The arrangement and manner of attaching the instrument parts is also of great advantage, since same may be very quickly disassembled for cleaning purposes.
- Having thus described the invention, what is claimed as new is—
1. In a veterinary instrument, the combination of a main shank, a head adjustable upon said shank, and an embryotome movably mounted upon head.
  2. In a veterinary instrument, the combination of the main shank, a head having adjustable threaded connection with said main shank, the embryotome movably mounted upon the head, said head being adapted to be adjusted to effect engagement of the shank with the embryotome.
  3. In a veterinary instrument, the combina-

tion of a main shank, an embryotome comprising a shank revolvably mounted upon the main shank, and a knife pivoted to said revolvable shank.

4. In a veterinary instrument, the combination of a shank having a tubular portion, a head received by said tubular portion, and an embryotome mounted upon said head, the shank coöperating with the embryotome to hold same in position.

5. In a veterinary instrument, the combination of a main shank provided at one end with a handle and at the other end with a tubular portion, a head threaded into the tubular portion and provided with a longitudinal slot therein, an embryotome comprising a knife having a shank swiveled in the slot of the head, a pivotal connection between the knife and its shank, the main shank being adapted to engage the shank of the embryotome to hold the latter in position.

In testimony whereof I affix my signature in presence of two witnesses.

HENRY M. STEVENSON. [L. s.]
